V. H. JACKSON.
CABLE GRIP.
APPLICATION FILED NOV. 3, 1915.

1,192,065.

Patented July 25, 1916.

UNITED STATES PATENT OFFICE.

VILAS H. JACKSON, OF CLEVELAND, OHIO.

CABLE-GRIP.

1,192,065.

Specification of Letters Patent.

Patented July 25, 1916.

Application filed November 3, 1915. Serial No. 59,413.

To all whom it may concern:

Be it known that I, VILAS H. JACKSON, a citizen of the United States, residing at Cleveland, in the county of Cuyahoga and State of Ohio, have invented certain new and useful Improvements in Cable-Grips, of which the following is a specification, reference being had to the accompanying drawings.

10 This invention relates to an improved cable grip and has for its primary object to provide a cable grip which may be easily and quickly attached to the cable section connected to the load, said grip being connected to the drum cable so that a pull upon the latter cable will constantly act to more tightly retain the grip in its applied position.

15 It is another object of my invention to provide a cable gripping device, the several parts of which are so constructed and arranged that the grip will withstand very severe usage without injury to the parts thereof or, in any way, affecting their operation in subsequent use.

20 In its more specific aspect, the invention contemplates the provision of a plurality of cable gripping jaws having means for interlocking engagement with each other, means 25 having sliding wedging action upon said jaws to force the same into gripping engagement upon a cable, and actuating levers connected to the latter means and operated by a pull upon the drum cable to force the jaws into gripping engagement with the connected cable.

25 The invention has for another important object to provide simple and reliable means for holding the several gripping jaws in assembled relation and preventing their relative shifting movement when out of engagement with the cable.

30 The invention has for a further general object to provide a device of the above character which may be advantageously employed as a cable grip in the pulling of tree stumps, as well as in mining, excavating, bridge building, and various other engineering operations.

35 With the above and other objects in view, my invention consists in the novel features of construction, combination and arrangement of parts to be hereinafter more fully described, claimed, and illustrated in the accompanying drawing, in which,

Figure 1 is a plan view illustrating the

preferred embodiment of my improved cable grip; Fig. 2 is a side elevation thereof; Fig. 3 is a horizontal section; Fig. 4 is a section taken on the line 4-4 of Fig. 3; and Fig. 5 is a perspective view of one of the gripping jaws.

Referring in detail to the drawing, 5 designates the cable gripping jaws which are of practically the same form and construction. Each jaw consists of a solid metal bar, preferably steel, having a maximum thickness at its center and being longitudinally tapered or inclined to the opposite ends of said bar on its exterior face, as indicated at 6. The jaw is of arcuate cross-sectional form having a maximum width of 90°. The inner face of the jaw extends in a continuous line and has spiral corrugations 7 cut therein which extend throughout the length of the jaw. Upon each longitudinal edge of the jaw, spaced rectangular teeth 8 are formed, and the teeth on the edges of the several jaws are so related with respect to the teeth on the adjacent jaws that said teeth will have interfitting engagement with each other. At the opposite end of each of the jaws 5, the inner end edge thereof is rounded or convex, as shown at 9, so that the cable may be readily threaded through the assembled jaws. One pair of the jaws 5 which are diametrically opposed to each other, are provided in their outer faces and adjacent to their opposite ends with the longitudinally extending grooves or channels 10 for a purpose which will be hereinafter pointed out. Each of the jaws 5 is further provided in its inner face and at its approximate center with a transversely extending groove 11 and, at the center of said groove, a cylindrical socket 12 is formed in the jaw. The grooves 11 receive a ring or collar 13, and in each of the sockets 12 a coil-spring 14 is arranged. These springs acting upon the collar 13 and the respective jaws, act to hold the jaws out of frictional contact with the cable when the jaws have been released from their gripping engagement upon said cable.

Upon the tapering end portions of the jaws 5, the longitudinally sliding cones 15 are engaged. Each of these cones is formed upon its opposite sides with the outwardly projecting, spaced ears 16. In the ears on one cone, pivot bolts 17 are engaged. Upon these pivot bolts, the inner ends of the levers 18 are loosely mounted. Links 19 are pivotally connected at one of their ends, as at 20,

to the respective levers 18 adjacent the pivot 17 thereof, and the other ends of said links are pivotally engaged upon the bolts 21 connecting the spaced ears 16 of the other cone 5 15. In each of the cone members between the spaced ears 16 thereon, a set screw 22 is threaded, and the inner ends of these set screws are engaged in the grooves or channels 10 of the opposed jaws 5.

10 To the outer ends of the levers 18, clevis rods or links 23 are pivotally connected, the other ends of said links being connected together by a clevis bolt 24 upon which the ends of the clevis 25 are engaged. To this 15 clevis 25, the drum cable, indicated at C, is adapted to be connected. C' designates the cable which is connected to the load.

In the practical operation of the device, cable C' is slipped through the grip longitudinally between the jaws 5, said jaws being in their released positions as indicated in dotted lines in Fig. 1. When the winding drum is operated, the cable C will be wound thereon, and the levers H will be 25 pulled to the positions indicated in full lines in Fig. 1 so that the cones 15 will be shifted inwardly upon the relatively thick central portions of the jaws 5 in opposite directions and said jaws thus forced inwardly to cause 30 the corrugated inner faces 7 thereof to securely grip upon the cable. It will be readily seen that the greater the load and, therefore, the power which is required to pull the same, the greater will be the gripping 35 pressure of the jaws upon the cable through the medium of the levers 18 and links 19. The gripping device may be attached to the cable C' at any point along its length in spaced relation to the load, so 40 that the drum can be started empty, and injury to the cable or drum thus obviated as sometimes occurs through overwinding. The load may be attached to or released from the device very quickly. Owing to the 45 provision of the set screws 22 in the cones 15 which bear against the base walls of the channels or grooves 10, said cone members will occupy corresponding positions upon the opposite ends of the jaws 5, their outward 50 longitudinal movement upon the jaws being limited by the set screws. The screws also serve to maintain the jaws 5 in their proper relative positions and prevent turning or rotative movement of the same within 55 in the cones 15.

As previously noted, the jaws, when released, are held out of frictional engagement with the cable by the springs 14 while the ring or collar 13 prevents relative longitudinal movement of the jaws. Thus, it will be seen that each of the jaws has precisely the same gripping effect upon the cable, said jaws operating in the manner of an expanding and contracting cylinder on all parts of 65 the circumference of the cable, the pressure

being equally distributed throughout the length of the jaws. As the mechanical construction of my improved cable grip is quite simple, it will be seen that the device is extremely durable and capable of withstanding the severe use to which such devices are ordinarily subjected. It will be manifest that the size of the jaws and the internal diameter of the cones may be considerably varied so as to enable the grip to be applied 75 to cables of different sizes.

From the foregoing description, taken in connection with the accompanying drawing, the construction, manner of operation and several advantages of the invention will 80 be clearly and fully understood.

In the drawing, I have disclosed what I believe to be the preferred form and relative proportions of the several parts; but it will be understood that I do not desire to be 85 at all restricted in this respect as various changes may be necessitated as the particular exigencies of the case, encountered in the use to which the device is to be applied, may indicate to be desirable. I desire it also 90 to be understood that, while I have above referred to a certain relative arrangement of the several coöperating elements, the invention might also be produced in other modified forms and I, therefore, reserve the 95 privilege of adopting all such legitimate changes as may be fairly embodied within the spirit and scope of the invention as claimed.

Having thus fully described my invention, 100 what I desire to claim and secure by Letters Patent is:—

1. A cable grip including a plurality of gripping jaws each having its outer face inclined, opposed relatively slidable elements 105 engaged upon the inclined faces of the jaws, operating connections between said elements, and means connected to said operating connections to actuate the same and simultaneously shift said elements upon the 110 relatively stationary jaws to force the jaws into gripping engagement upon a cable arranged between the same.

2. A cable grip including a plurality of jaws having their outer faces tapered from 115 the center of the jaw to its opposite ends, cones slidably engaged upon the tapering end portions of said jaws, levers connected to one of the cones, means for connecting said levers to a pulling cable at their outer ends, and links connecting said levers adjacent their other ends to the other cone, whereby said cones are moved inwardly upon the jaws in the operation of the drum to simultaneously force said jaws inwardly 125 into gripping engagement upon the cable.

3. A cable grip including a plurality of jaws having their outer faces tapered from the center of the jaw to its ends, cones slidably upon the tapered end portions of the 130

5 jaws, means connecting the cones to each other for relative movement toward or from each other upon the jaws, actuating means connecting the latter means to a pulling cable whereby the cones are moved inwardly upon the jaws by the pull of said cable and the jaws forced inwardly into gripping engagement with a second cable, and means carried by each of the cones co-operatively engaged with the opposed jaws to limit the outward sliding movement of the cones and also prevent turning movement of the jaws within said cones.

10 4. A cable grip including a plurality of jaws each having its outer face tapered from the center of the jaw to its ends, opposed cones slidably upon the tapered end portions of the jaws toward or from each other, and operating connections between said cones to simultaneously shift the same inwardly upon the jaws toward each other and exert a radial pressure upon the relatively stationary jaws to cause the same to grip upon a cable arranged between said jaws.

15 5. A cable grip including a plurality of jaws having their outer faces tapered from the center of the jaw to its ends, cones slidably upon the tapered end portions of the jaws, means connecting the cones to each other for relative movement upon the jaws, means for connecting the latter means to a pulling cable whereby the cones are moved inwardly upon the jaws by the pull of said cable and the jaws forced inwardly into gripping engagement with a second cable, means carried by each of the cones co-operatively engaged with the opposed jaws to limit the outward sliding movement of the cones and also prevent turning movement of the jaws within said cones, and additional means for holding the jaws out of frictional contact with the cable when the cones are moved to their released positions, and also preventing relative longitudinal shifting movement of the jaws.

20 6. A cable grip including a plurality of jaws having their outer faces tapered from the center of the jaw to its ends, cones slidably engaged upon the tapered ends of the jaws, the inner face of each jaw being transversely grooved at its center, a collar seated in said grooves to prevent relative longitudinal shifting movement of the jaws when in their released positions, and means connected to the cones for shifting the same simultaneously to force the jaws into gripping engagement upon a cable.

25 7. A cable grip including a plurality of jaws having their outer faces longitudinally tapered from the center of the jaw to its opposite ends, cones slidably engaged upon the tapered ends of the jaws, each of said jaws having a transverse groove at its center and in its inner face, a collar seated in

said grooves through which a cable is adapted to be engaged, each jaw having a socket centrally located at the base of the groove, a spring arranged in said socket and bearing against said collar, said springs operating to hold the jaws out of frictional engagement with the cable in the released positions of the jaws, said collar preventing relative longitudinal shifting movement of the jaws, and means for operating the cones simultaneously to force the jaws into gripping engagement upon the cable.

30 8. A cable grip including a plurality of jaws having their outer faces longitudinally tapered from the center of the jaw to its opposite ends, cones slidably engaged upon the tapered ends of the jaws, each of said jaws having a transverse groove at its center and in its inner face, a collar seated in said grooves through which a cable is adapted to be engaged, each jaw having a socket centrally located at the base of the groove, a spring arranged in said socket and bearing against said collar, said springs operating to hold the jaws out of frictional engagement with the cable in the released positions of the jaws, said collar preventing relative longitudinal shifting movement of the jaws, means for operating the cones simultaneously to force the jaws into gripping engagement upon the cable, and means carried by each cone co-operating with the opposed jaws to limit the outward sliding movement of the cone upon the jaws.

35 9. A cable grip including opposed jaws each having its outer face longitudinally tapered from its center to its opposite ends, longitudinally slidible elements engaged upon the tapering end portions of said jaws, means preventing relative longitudinal shifting movement of the jaws, and means operatively connecting said elements to simultaneously shift the same inwardly toward each other upon the jaws and force the jaws radially into gripping engagement upon a cable arranged between the same.

40 10. A cable grip including a plurality of jaws having means on their longitudinal edges for interlocking engagement with each other, the outer faces of said jaws being longitudinally tapered from the center of the jaw to its opposite ends, cones longitudinally slidable upon the tapering ends of the jaws, and means for operating the cones simultaneously to force the jaws into interlocking engagement with each other and into gripping engagement upon a cable disposed between said jaws.

45 11. A cable grip including a plurality of jaws having corrugated inner faces and teeth on their longitudinal edges, the outer faces of said jaws being tapered from the center of the jaw to its opposite ends, cones slidable upon the tapered end portions of the jaws, means for operating the cones

simultaneously to force the toothed edges of the jaws into interlocking engagement with each other and the corrugated faces of the jaws into gripping engagement upon 5 a cable disposed between the jaws, and means carried by each of the cones and co-operating with the opposed jaws to limit the outward sliding movement of the cones

and prevent a rotative movement of the jaws therein.

10

In testimony whereof I hereunto affix my signature in the presence of two witnesses.

VILAS H. JACKSON.
